CLAIM

I claim the ornamental design for a single pet bowl, as shown and described.

DESCRIPTION

FIG. 1 is a top right corner perspective view of the single pet bowl showing my new design;

FIG. 2 is a bottom left rear corner perspective view thereof;

FIG. 3 is a front elevation view thereof with the rear elevation view being identical;

FIG. 4 is a right side view thereof with the left side view being identical;

FIG. 5 is a top plan view thereof; and,

FIG. 6 is a bottom view thereof.
